PISTON SKIRT EXPANDER

Roy W. Paton, Hagerstown, Ind., assignor to The Perfect Circle Company, Hagerstown, Ind., a corporation of Indiana

Application May 16, 1934, Serial No. 725,839

9 Claims. (Cl. 309—12)

This invention relates to means for expanding the split skirt of a piston for internal combustion engines, and the like, to eliminate piston "slapping", excessive oil consumption and blow-by and other defects.

One of the objects of the invention is to provide a novel piston skirt expander formed of flat spring metal which is simple in construction, efficient in use and readily applicable to the piston skirt.

Another object is to provide an expander of the foregoing character which is provided with a novel arrangement of expanding formations well adapted for use with so-called "T-slot" pistons.

A more specific object is to provide an expander having upper and lower sections which are provided with expandable formations adapted to cooperate with piston skirt walls having oppositely-disposed slots that extend, respectively, from the opposite ends of the piston skirt and only partly throughout the length of such skirt.

Other objects and advantages will become apparent as this description progresses and by reference to the drawing wherein,—

Figure 1 is a side view of a so-called "T-slot" type of piston, the skirt portion of the piston being partially broken away to show an expander embodying my invention in position therewithin;

Fig. 2 is a section taken substantially on line 2—2 of Fig. 1;

Fig. 3 is a bottom plan view of the structure of Fig. 1;

Fig. 4 is a separated perspective view of the expander shown in the previous figures;

Fig. 5 is a separated perspective view of the upper section of the expander shown in Fig. 4; and

Fig. 6 is a perspective view of the lower section of the expander of Fig. 4.

The structure shown in the drawing includes a piston formed preferably of aluminum alloy and having a head 10 and a skirt 11 which is separated from the head 10 throughout a portion of its circumference by a horizontal slot 12. The skirt 11 is provided with a vertically-extending slot 13 which extends from the upper end of the skirt only partially throughout the length of the latter as best shown in Fig. 1. This upper end of this slot 13 joins with substantially the central portion of the head-separating slot 12 whereby the two slots 12 and 13 provide a T-shaped slot formation permitting expansion and contraction of the piston skirt as will be well understood.

The piston skirt integrally supports piston pin bosses 14 which carry a piston pin 15.

In carrying out this invention, the skirt wall directly opposite the slot 13 is provided with another slot 16 which extends from the lower end of the piston skirt only partially throughout the length thereof as shown in Fig. 2. If the slot 16 is not normally provided in the piston skirt, it may be readily formed therein at the time of the servicing operation in which the expander is applied.

The expander includes an upper section 17 and a lower section 18, each formed of a strip of spring steel bent to a rectangular-like closed figure shape. The free ends of the upper section are curled or curved to provide expandable and contractible skirt wall contacting portions 19. 15 The rear or closed end of this section is bent inwardly as at 20 providing spaced bends 21 and 22 which engage the piston skirt wall at points opposite the free ends 19. The lower section 18 is provided with similarly-formed and shaped free 20 ends 23 and bends 24. The free ends 19, 23 and the bends 21, 22, 24 are provided with rather sharp lips 25 which bite into the metal of the piston skirt and securely anchor the expander therein. 25

The upper expander section 17 is provided with side portions 26 having downwardly-extending arms 27 adapted to be secured by rivets 28 (or other suitable fastening devices) to the side portions 29 of the lower section 18. The side portions 26 of the upper section are provided with aligned openings 30 which, in the assembled position of the expander, align with the openings 31 in the piston pin bosses 14 so that the piston pin 15 passes therethrough. 35

The free curved ends 19 of the upper section are adapted to engage the piston skirt wall adjacent the slot 13, and the curved ends 23 of the lower section are adapted to engage the skirt wall adjacent the slot 16 (Fig. 3). To this end, and 40 in view of the vertical staggered relation of the opposed slots 13 and 16, the upper and lower sections are secured together in such a manner that the free ends 19 and 23 of these sections are located at opposite ends of the expander. The 45 arrangement is such that the free ends of the lower section 18 are located beneath and in alignment with the closed end and the bends 21, 22 of the upper section; and the closed end and bends 24 of the lower section are beneath and in alignment with the free ends 19 of the upper section 17. The attachment arms 27 of the upper section are of such length that the end portions of the expander sections are spaced apart. This 50 spacing is such that, when the expander is ap- 55

plied to the piston (Fig. 2), the closed end of the upper section 17 abuts the skirt wall above the slot 16 with its free ends straddling the slot 13 at the other side of the skirt, and the closed end of the lower section 18 abuts the piston skirt beneath the lower end of the slot 13 with its free ends straddling the slot 16 at the other side of the skirt.

The expander is of such size and shape that, when it is contracted by hand or other means and placed within the skirt and then released, the opposite ends of the expander sections press firmly in opposite directions against the skirt wall, and the sides of the expander bow outwardly so that they seat firmly against and apply expanding pressure to the facing surfaces of the piston pin bosses 14. In this manner the skirt is expanded and it is maintained in expanded condition. By arranging the free ends of the upper and lower expander sections 17 and 18 alternately as described so as to cooperate with the staggered slots 13 and 16, the expansion action is substantially uniform and the avoidance of piston slap, excessive blow-by and oil consumption is accomplished in an efficient manner. The foregoing action is aided by the vertical bends 32 in each of the sections adjacent their respective side portions 26 and 29.

It will be understood that, while only one form of structure embodying the invention has been illustrated and described, other changes in details and arrangements of parts may be made without departing from the spirit and scope of the invention as defined by the claims which follow.

I claim:

1. A piston skirt expander which comprises a pair of sections each formed of a strip of spring metal bent to a generally polygonal shape with one end portion continuous and the other end portion provided with free ends, and means securely fastening said two sections together with the free end portion of one section vertically aligned with and spaced from the continuous end portion of the other section.

2. A piston skirt expander which comprises a pair of sections each formed of a strip of spring metal bent to a generally polygonal shape with one end portion formed continuous and the other end portion provided with free ends, one of said sections having its opposite sides extended downwardly and provided with openings to receive a piston pin or the like, and means for fixedly securing the lower ends of said side extensions to the other of said sections with the end portions of said latter section reversed with respect to the end portions of said one section.

3. A piston skirt expander which comprises a pair of sections each formed of spring metal to a generally rectangular shape and having free ends at only one end thereof, the sides of one of said sections being provided with openings to receive a piston pin, said sides being extended for securing to the sides of the other of said sections, and means fixedly securing said side portions of said sections together with the free ends thereof at opposite ends of the expander and with the adjacent ends of said sections vertically spaced apart.

4. A piston skirt expander which includes a pair of sections each formed from a strip of spring metal to a generally polygonal shape, each said section being continuous at one end portion with spaced apart wall-contacting points therein and being provided at its other end portion with

free ends curved for expansible skirt wall engagement, the side walls of one of said sections being provided with extensions, and means securing the free ends of said extensions to the side walls of the other of said sections with the end portions of said sections reversed with respect to each other and with the adjacent end portions of the secured sections vertically spaced apart. 5

5. In combination with a piston having a skirt with opposed and vertically staggered slots therein, of a spring metal expander within and extending crosswise of said skirt and including a pair of attached sections each formed contiguous except for free ends at one end portion thereof, said free ends having expansible formations, 15 and said free ends of each section being disposed at opposite ends of the expander in vertically staggered fashion and engaging the interior of the piston skirt in straddle relation with respect to the respective of said vertically staggered slots. 20

6. In combination with a piston having a skirt with substantially diametrically opposed slots therein, one extending partially throughout the length of the skirt from the upper end thereof and the other extending partially throughout the length of the skirt from the lower end thereof, of a spring metal expander in the form of a closed figure mounted crosswise within said skirt and including upper and lower sections secured together, said upper section being continuous at 30 one end portion and having a pair of free ends at its other end portion located to engage said skirt wall on opposite sides of said first-mentioned slot and said lower section being similarly formed and having its free ends located to engage the wall of said skirt on opposite sides of said second mentioned slot.

7. In combination with a piston having a skirt with opposed and vertically staggered slots therein, one of said slots extending from the upper end of said skirt and the other from the lower end of said skirt, of a spring metal expander mounted within said skirt and having upper and lower sections of general rectangular shape, each of said sections having one end 40 formed continuous and its other end provided with a pair of free ends, said sections being secured together with their respective free end portions at opposite ends of the expander, the ends of said sections being engaged with the skirt wall with the free ends of said sections straddling the respective of said opposed slots.

8. In combination with a piston having a skirt with opposed and vertically staggered slots therein, one of said slots extending from the upper end of said skirt and the other from the lower end of said skirt, of a spring metal expander mounted within said skirt and having upper and lower sections of general rectangular shape, each of said sections having one end formed continuous and its other end provided with a pair of free ends, said sections being secured together with their respective free end portions at opposite ends of the expander, the arrangement being such that the continuous ends of said sections engage the skirt wall adjacent the ends of said opposed slots, and said free ends straddle said slots intermediate the ends of the latter.

9. In a combination with a piston having a skirt with a vertical slot at one side extending 70 from the upper end of the skirt and terminating short of its lower end and a second opposed and vertical slot extending from the lower end of said skirt and terminating short of the upper end of the latter, of expanding means mounted 75

crosswise of said skirt and having end and side portions adapted to engage said skirt in the direction of said slots and laterally thereof, respectively, and expanding means including a device having at each end thereof a pair of free ends vertically spaced from a continuous end portion, the free ends at opposite ends of said de-

vice being vertically offset with respect to each other and engaging the wall of said skirt on the opposite sides of the respective of said slots with said continuous end portions also engaged with the wall of said skirt.

ROY W. PATON.

CERTIFICATE OF CORRECTION.

Patent No. 2,023,613.

December 10, 1935.

ROY W. PATON.

It is hereby certified that error appears in the printed specification of the above numbered patent requiring correction as follows: Page 3, first column, line 4, claim 9, for "and" read said; and that the said Letters Patent should be read with this correction therein that the same may conform to the record of the case in the Patent Office.

Signed and sealed this 28th day of January, A. D. 1936.

Leslie Frazer
Acting Commissioner of Patents.
